UNITED STATES PATENT OFFICE.

SIMON COOPER, OF BROOKLYN, NEW YORK.

MOLD AND PROCESS FOR FORMING ARTICLES FROM PULP OR OTHER PLASTIC MATERIAL.

Continuation of application Serial No. 488,679, filed July 30, 1921. This application filed April 7, 1922.
Serial No. 550,261.

To all whom it may concern:

Be it known that I, SIMON COOPER, a citizen of the United States, residing at Brooklyn, in the county of Kings and State of New York, have invented certain new and useful Improvements in Molds and Processes for Forming Articles from Pulp or Other Plastic Material, of which the following is a specification.

10 This is a continuation of my former application Serial No. 488,679 filed July 30, 1921, and it is intended to secure in this application the benefit of the filing date of my said former application so far as concerns

15 the subject-matter disclosed in common in both applications.

My invention relates particularly to that type of process wherein a deposit of the pulp or pulp-like material is obtained by 20 first applying suction to the exterior of a porous mold whose interior is in communication with a body of the more or less liquid or plastic material and then releasing the suction and freeing the deposited 25 wall of excess material. There is sometimes a tendency in such processes for the column of material, as it rises in the mold, to become depleted before it reaches the top of the mold, resulting in a weaker deposit of pulp 30 at the top than elsewhere. This is a disadvantage in the case of bottles and the like, which are molded in inverted position because it results in the bottom of the bottle (the top part in the mold) being the weakest part of the article.

The primary object of my invention is to overcome this fault, and this I have done by introducing into the mold at the proper time a supplementary supply of material to 40 augment or reinforce the deposit at the top of the mold.

In the accompanying drawing I have illustrated a practical embodiment of means for carrying out this invention, wherein 45 Figure 1 is a view in side elevation of the complete apparatus; and Figure 2 is a vertical sectional view taken through the suction chamber and pulp reservoir.

Considering the illustration in detail: 50 designates a suitable pump or suction-producing device, connected by piping 6, with the vacuum or suction chamber 7, a vacuum tank 8, of appropriate size being interposed in this line of piping to overcome pulsations

of the pump and provide a certain "re- 55 serve" of suction force.

Within the suction chamber is mounted the mold, having porous walls 9 of gauze or the like conformed to the shape of the article to be produced, a milk bottle in the case illustrated, and braced by suitable ribbing 10. The base 11 of the mold is also porous and the mold is preferably made in sections to enable ready removal of the molded product therefrom. This mold is 60 supported in an inverted position on a hollow column or tube 12, whose lower end dips into a pulp reservoir 13.

The usual mode of operation is, by means of a finely regulatable valve 14 (valve 20 70 being closed and valves 24 and 25 open), to admit first a reduced degree of suction to the suction chamber so as to fill the mold gradually, rather than suddenly as would happen if valve 20 were opened suddenly. 75 As the column of pulp rises in the mold, the liquid and lighter particles pass through the interstices or pores, leaving a layer of pulp deposited on the walls of the mold, this deposit progressing as the pulp rises. 80 This gradual movement results in a well matted or felted facing deposit and is followed by an interval of full suction to increase the thickness of deposit.

There is a tendency for the mixture to 85 become weakened or depleted in strength before it reaches the top of the mold. To overcome or offset this weakening effect, I admit a supplementary supply of material to that portion of the mold where reinforcement is necessary or desirable. In the drawing this is done by means of a conduit 15, dipping into the pulp reservoir and extending up into the upper portion of the mold, where it terminates in a funnel-shaped spout 16, disposed quite close to the top of the mold. This conduit is shown controlled by a valve 17, and said valve is indicated as of the two-way type for also controlling a connection 18, to atmosphere. 90 95

The usual method of utilizing the additional or supplementary pulp supply thus afforded is to open valve 17, to the pulp supply just as the rising column of mixture reaches the top and the mold chamber becomes filled. This causes a supplementary deposit of fresh undiluted pulp to be superimposed upon the deposit made on the top of 100 105

the mold, and this movement may begin simultaneously with the initiation of the period of full suction mentioned above. The desired thickness of deposit on all parts of 5 the mold having been secured, the valve 17 is operated to open up the passage to atmosphere. This releases the suction effect, gradually producing an equilibrium of pressure at the top and base of the pulp column, as 10 the incoming air slowly passes through the deposited pulp, thereby allowing the excess pulp to drain slowly back into the reservoir.

The valve 17 is then closed against both pulp and atmosphere, and after breaking 15 connection with the pulp supply, as by lowering the reservoir on its pivots 19, out of the range of the pipe connections 12, 15, the mold is subjected to the full suction effect as by opening up a main control valve 20. 20 This carries off free liquid in the mold and compacts the deposit, leaving the molded article in such state that it may be removed from the mold for further treatment or be left in place therein for subsequent treatment. 25

The suction chamber may be made in the form of a bell detachably engaged with the supporting base 21 to enable the ready removal of the mold. Before opening the 30 chamber, it is usually freed of any liquid that may have gathered therein by opening up the valve 23 in the drain pipe 22.

It will be evident that the reinforcing effect may be varied, for instance, by opening 35 up the supplementary pulp supply at different periods in the filling of the mold chamber. Thus by opening up this supple-

mentary supply before the mold is filled, the reinforcing deposit may be applied or begun before the main deposit is made. 40

I claim:

1. The process of molding, which comprises applying suction to the exterior of a porous mold whose interior is in communication with a body of pulp-like material, establishing connection between said body of material and the interior of the mold through a supplementary conduit and then opening the interior of the mold to atmosphere through said same supplementary 50 conduit.

2. The process of molding, which comprises applying suction to the exterior of a porous mold whose interior is in communication with a body of pulp-like material, establishing a supplementary connection between the interior of the mold and a supply of material and then opening the interior of the mold to atmosphere through 55 said supplementary connection. 60

3. In combination, a pulp supply tank, a suction chamber, a porous mold in said suction chamber having an inlet in said tank, and a conduit opening into the mold chamber and having an inlet in the tank. 65

4. In combination, a pulp supply tank, a suction chamber, a porous mold in said suction chamber having an inlet in said tank, a conduit opening into the mold chamber having an inlet in the tank and opening to atmosphere, and means controlling said inlet and opening to atmosphere. 70

In testimony whereof I affix my signature.
SIMON COOPER.
